(57) CLAIM

The ornamental design for a hand-held cleaning device, as shown and described.

DESCRIPTION

FIG. 1 is a perspective view of a hand-held cleaning device; FIG. 2 is a top view thereof, the bottom view being a mirror image thereof;

FIG. 3 is a right side view thereof, the left side view being a mirror image thereof; and,

FIG. 4 is a front view thereof, the rear view being a mirror image thereof.

The surface shading illustrated in the drawings is provided merely to highlight the contour of the design; it is not intended to be illustrative of texture or gloss.
